(57) **CLAIM**

The ornamental design for a safe, as shown and described.

DESCRIPTION

FIG. 1 is a front, right and top perspective view of a safe, showing my new design, with the door in an open position; FIG. 2 is a front, left and top perspective view of FIG. 1; FIG. 3 is a rear, left and bottom perspective view of FIG. 1; FIG. 4 is another front, right and top perspective view thereof, with the door in a closed position;

FIG. 5 is a front view of FIG. 1;

FIG. 6 is a rear view of FIG. 1;

FIG. 7 is a left side view of FIG. 1;

FIG. 8 is a right side view of FIG. 1;

FIG. 9 is a top plan view of FIG. 1;

FIG. 10 is a bottom plan view of FIG. 1;

FIG. 11 is an enlarged portion view of encircled portion, "11," in FIG. 2;

FIG. 12 is an enlarged portion view of encircled portion, "12," in FIG. 2; and,

FIG. 13 is an enlarged portion view of encircled portion, "13," in FIG. 2.

The even broken lines shown in the drawings illustrate portions of the safe that form no part of the claimed design. The dot-dash broken lines depict the boundaries of the enlarged portion views of FIGS. 11-13 shown in FIGS. 2 and 11-13 and form no part of the claimed design.

1 Claim, 13 Drawing Sheets
